CLAIM

The ornamental design for sandpaper as shown and described.

DESCRIPTION

FIG. 1 is a front top perspective view of sandpaper showing our new design;

FIG. 2 is rear top perspective view of the design shown in FIG. 1;

FIG. 3 is a top plan view of the design shown in FIG. 1;

FIG. 4 is a front elevational view of the design shown in FIG. 1;

FIG. 5 is a bottom plan view of the design shown in FIG. 1; FIG. 6 is a left side elevational view of the design shown in FIG. 1, the right side elevational view being a mirror image thereof; and,

FIG. 7 is a rear elevational view of the design shown in FIG. 1.

The broken lines define the bounds of the claimed design and form no part thereof. The area between the broken lines and the solid lines do not form part of the claimed design.
